UNITED STATES PATENT OFFICE

148,287

DESIGN FOR A WHEELBARROW

Joseph A. Cravero, East Farmingdale, Long Island, and Addison S. Milligan, Farmingdale, N. Y., said Milligan assignor to said Cravero

Application November 25, 1946, Serial No. 135,074

Term of patent 14 years

(Cl. D14—3)

To all whom it may concern:

Be it known that we, Joseph A. Cravero and Addison S. Milligan, citizens of the United States, and respectively residents of East Farmingdale, Long Island, New York, and Farmingdale, Long Island, New York, have invented a certain new, original, and ornamental Design for Wheelbarrow described and claimed in the following specification and shown in the accompanying drawings wherein:

Fig. 1 is a side elevation of a wheelbarrow embodying the present design;

Fig. 2 is a top plan view thereof;

Fig. 3 is a front elevation thereof;

Fig. 4 is a rear elevation of the wheelbarrow embodying the present design.

What is claimed is:

The ornamental design for a wheelbarrow, substantially as shown.

JOSEPH A. CRAVERO.
ADDISON S. MILLIGAN.
